TROPICAL LOUVER CONSTRUCTION

William A. Andresen and Louis Boero, Chicago,
Ill., assignors to The Casement Hardware Company, Chicago, Ill., a corporation of Illinois

Application May 28, 1942, Serial No. 444,874

5 Claims. (Cl. 20—62)

Our invention pertains to improvements in tropical louver constructions of the kind having horizontally pivoted slats which can be opened or closed shutter-like and which are extensively used in tropical or semi-tropical climates for protection against storms and for excluding direct rays of the sun at the window openings of dwellings and other buildings, in many instances being the sole protective closures at the window openings.

One of the objects of our invention is to simplify and improve the construction of tropical louvers and facilitate the installation thereof, while at the same time making such louvers more efficient for the intended purposes.

Another object is to provide in a tropical louver construction a novel arrangement of pre-assembled hardware units which can be easily and quickly installed in the frame of the opening to be closed by the louver.

Still another object of the invention is to provide a tropical louver construction in which the louver slats can be conveniently assembled with the louver hardware after the latter has all been installed.

A further object of the invention is to provide a tropical louver construction which is equipped in a novel manner to serve effectively not only for protecting the interior of the enclosure against rain and wind, but also to provide as complete as practicable a blackout of light from within the enclosure so that such light will not escape through the window opening, particularly at night during war time when there is danger of air raids or even ground invasions and no tell-tale light should be visible to assist the enemy in spotting the location of a building or finding his direction.

Another object is to provide hardware for tropical louver construction which can be made from simple and readily available materials by simple manufacturing processes at relatively low cost.

Other objects and advantages of our invention will appear more fully from the following description and from the accompanying drawings, in which similar characters of reference indicate similar parts throughout the several views.

Fig. 1 is a front elevational view of a window opening equipped with a tropical louver embodying the features of our invention;

Fig. 2 is a fragmental horizontal sectional view through the window frame and the tropical louver taken substantially along line 2—2 of Fig. 1;

Fig. 3 is a vertical sectional view through the window and louver taken substantially along line 3—3 of Fig. 1;

Fig. 4 is a fragmentary horizontal sectional view on an enlarged scale taken substantially along line 4—4 of Fig. 3;

Fig. 5 is a side elevational view of one of the slat-carrying units of the louver hardware;

Fig. 6 is a side elevational view of the opposite slat-carrying unit of the louver hardware;

Fig. 7 is an enlarged perspective view of one of the slat-end carriers before assembly in the carrying unit; and

Fig. 8 is an inside perspective view of one of the blackout and weather strips which in assembly 10 are associated with the slat carriers.

A tropical louver 10 embodying the features of our invention is shown in the drawings as installed within a window opening of a wooden building where the louver provides the sole closure for the window opening. At the sides, the window opening is defined by conventional jambs 11 and 12 capped by a lintel 13 and surmounting a sill 14 which has a forwardly beveled drainage lip 15 as is customary. Side and top molding or finishing strips 17 and 18, respectively, are secured about the window opening at the outside of the building.

The louver 10 proper comprises a series of horizontally extending wooden louver slats 19 which in the window closing relationship thereof overlap slightly at their horizontal edges. The lower inner horizontal edge of each slat is formed with a rabbet groove 20 which in each of the upper slats engages the upper outer horizontal corner of the slat immediately therebelow, and in the case of the lowermost slat, engages the upper forward corner of a stop strip 21. If preferred, of course, the slats 19 may be rabbet-grooved at their upper instead of lower edges. Herein the strip 21 serves also as a sill plate secured upon the rear portion of the sill 14 and has its top surface slanting outwardly to promote drainage. The upper outer horizontal margin of the uppermost louver slat 19 engages behind an upper horizontal sealing strip 22 set within a rabbet groove 23 in the forward lower edge of the lintel 13 behind the lower margin of the upper molding strip 18. Through this arrangement the louver is thoroughly storm-tight along all horizontal edges of the louver slats 19 and also completely light-proof, particularly against light escaping from within the building at night when blackout precautions must be exercised.

According to the present invention, the hardware for mounting the louver slats 19 is of a novel pre-assembled construction which can be quickly and easily installed by anyone possessed of even meager carpentry skill and which after installation is simple and easy to operate, but functions efficiently, positively, and enduringly. To this end, the hardware comprises a pair of pre-assembled slat-carrying units 24 and 25 adapted to be mounted upon the jambs 11 and 12, respectively, and a louver-operating unit 27 which is adapt-

ed to be manipulated for opening and closing the louver slats.

The slat-carrying unit 24 (Figs. 2, 4 and 5) includes a jamb strip 28 of right-angular cross section and of a length to extend from the lintel 13 to the sill 14. One flange 29 of the jamb strip is adapted to be secured by means such as nails 30 to the window margin of the outer face of the jamb 11, preferably flush within a shallow rabbet groove 31 of about the same depth as the thickness of the flange. The flange 29 is secured in place before the associated side finishing strip 17 is secured in overlying relation thereto. The remaining flange of the jamb strip, identified by the numeral 32, is adapted to extend rearwardly parallel to and preferably slightly spaced from the adjacent vertical face of the jamb strip 11, and may, as shown, be notched out as at 33 at its lower rear corner to receive the forward edge portion of the stop strip 21.

At equally spaced vertical intervals, the jamb strip flange 32 has pivotally secured thereto by means of rivets 34, identical slat carriers 35 (Figs. 3 and 5). These carriers are preferably formed from light gauge sheet metal and are of outwardly opening channel shape, having a web 37, and outer and inner integral parallel side flanges 38 and 39, respectively. The spacing between the flanges 33 and 39 is preferably such as to receive the end edge portions of the respective slats 19 snugly therebetween. The length of the web 37 is about equal to the width of the louver slats 19. A bearing aperture 40 for the pivot rivets 34 is formed in the web 37 intermediate its length and preferably nearer the upper or inner end of the web than the opposite end (Fig. 7).

At its lower or outer end, the web 37 is closed off by means such as a right-angular integral retaining flange 41 which extends in the same direction as the side flanges 38 and 39 and is engageable with the lower or outer edge of the associated slat end. In the present instance, the inner corner of the lower or outer end of the slat carrier 35 is preferably notched out as indicated at 42 to provide a clearance corresponding to the lower margin overlap rabbet 20 of the associated louver slat. Through this arrangement, the slats 19 are adapted to be inserted in the carriers 35 by a transverse sliding movement starting at the upper or inner ends of the carriers substantially as indicated in dot-dash outline in Fig. 5.

No nailing or other direct attachment of the slats 19 in the carriers 35 is necessary after assembly, but the slats are locked in place in the carriers by respective bendable locking tongues 43 integral with the upper ends of the side flanges 38. Each of the locking tongues 43 has the base thereof weakened by an edge notch 44 to facilitate bending over into engagement with the adjacent horizontally extending edge of the associated slat. With the slat end locked in place, the carrier 35 forms, in effect, an unattached end cap therefor.

The slat-carrying unit 25 is largely the counterpart of the slat-carrying unit 24 and comprises an angular jamb strip 45 supporting pivotally mounted end cap slat carriers 47. The jamb strip 45 includes a flange 48 adapted to be secured by means such as nails 49 (Fig. 1) flush within a rabbet groove 50 in the outer edge of the jamb 12. Right-angular to the flange 48 is a rearwardly extending flange 51 in slightly spaced parallel relation to the adjacent face of the jamb 12 and parallel to the opposite jamb

strip flange 32. At its lower end, the flange 51 has a notch 52 corresponding to the notch 33 in the jamb strip flange 32 for receiving the forward edge of the stop strip 21.

The slat carriers 47 are pivotally secured intermediate their ends by rivets 53 to the outer face of the flange 51 and have inner and outer channel flanges 54 and 55, respectively, and an end retaining flange 57 for receiving the respective ends of associated slats 19 which are adapted to be slid into place from an initial position at the upper or inner ends of the carriers as indicated in dot-dash outline in Fig. 6. A slat locking tongue 58 is formed at the upper end of each of the respective carrier flanges 54 to be bent over along a line determined by bend-weakening notch 59 for retaining engagement with the adjacent edge of the associated louver slat 19.

It will be observed that the opposing jamb strip flanges 32 and 51 are of substantial width, as for example about $\frac{1}{8}$ inch wide, and the pivot rivets 34 and 53 are located in coaxial alignment in a common vertical plane at or near the longitudinal centers of such flanges. Therefore, rotation of either of the slat carriers 35 or 47, after assembly of the slat 19 therewith, will cause like rotation of the opposite carrier. Furthermore, in the closed condition of the louver, the backs of the slat carriers 35 and 47 substantially throughout their lengths oppose the respective adjacent jamb strip flanges, which affords an important advantage, as will be more fully explained hereinafter.

Pivotal movement of the louver slats 19 to any position from the fully closed position shown in full line in Fig. 3 to the fully open position, shown in broken outline, is effected through the medium of a vertical tilt bar 60 (Figs. 2, 3 and 5), which is connected pivotally by means such as rivets 61 to the back faces of tilt bar ears 62, in this instance formed integral with the pivoted slat carriers 35. As best seen in Figs. 5 and 7, the tilt bar ears 62 are formed as coplanar lateral extensions of the carrier web 37 and take the place of substantial upper or inner end portions of the inner channel flanges 39 of the slat carriers. By this arrangement, all of the slat carriers 35, and through the slats 19, the carriers 47, are integrated for simultaneous pivotal movement in response to actuation of the tilt bar 60.

Manual actuation of the tilt bar 60 may be effected by selected increments by the operating unit 27. In the present instance the unit 27 comprises a flanged housing 64 which is secured by means of screws 65 to the jamb 11 at a convenient height behind one of the louver slats 19. The end of a removable hand crank 67 is received within a rearwardly opening axial socket 68 in a worm 69 which meshes with a sector gear 70 mounted therebelow for rotation in a plane parallel to the adjacent window face of the jamb 11. An arm 71 rigid with the sector 70 is pivotally connected removably by means of a pin 72 and a cotter key 73 to the lower end of a connecting link 74. The latter has its upper end pivotally connected between the tilt bar 60 and the ear 62 of the adjacent slat carrier 35 by means of the selected pivot rivet 61.

In the closed condition of the louver, the arm 71 preferably extends at substantially right angles to the tilt bar 60 and the connecting link 74 extends substantially vertically or slightly tilted forwardly like the slats 19. Thus, as the worm 69 is cranked to drive the sector 70 and swing the arm 71 in an arc down toward the

more or less vertical dot-dash position shown in Fig. 3, the link 74 draws the tilt bar 60 down to tilt the slats 19 open to any selected incremental degree up to the fully open limit indicated by the dot-dash outline position of the louver slats in Fig. 3.

In any position of the slats 19, the worm gear 68 and the sector 70 cooperate to hold the assembly against accidental movement out of the selected open or the closed condition of the louver. This arrangement also avoids any need for equipping the louver with a night latch or lock since once it has been cranked closed, it cannot be opened from the outside but requires that the worm 68 be rotated by the crank 67 to effect any movement.

The operating unit 27 may be located within the rear edge plane of the jambs 11 and 12 so that a fly screen 78 may be secured across the back of the window opening in any preferred manner. As illustrated in a conventional manner, the screen is held in position by means of a frame of molding strips 77, but any other more finished manner of mounting or securing may be employed. If it is preferred to apply the fly screen across the front of the window opening, the louver may be mounted further rearwardly so that the outwardly swinging lower edges of the slats 19 will clear the inside face of such screen.

While the overlapping relationship of the horizontal edges of the louver slats 19 provides an adequate weather and blackout seal for such edges, the practical, effective sealing of the necessary operating clearance spacing between the ends of the louver slats 19 and the mounting hardware has presented a considerable problem. We have solved this problem simply, effectively and economically by the provision of thin, resilient take-up strips 78 which are interposed between the back faces of the slat carriers 35 and 47 and the opposing faces of the jamb strip flanges 32 and 51, respectively. For this purpose, slightly more space is provided for between the slat carriers and the associated jamb strip flanges than might ordinarily be allowed. The resilient strips 78 are in channel form, transversely bowed outwardly and have opposed parallel side flanges 79 of substantial width for sealingly engaging the sides of the associated slat carriers. The strips 78 are of the same length as the slat carriers and are each formed with an aperture 80 for passage of the associated carrier pivot rivet by which the strip is held against longitudinal displacement from the carrier. The same form of the sealing strips applies to both the carriers 35 and 47 except that the inner side flanges 79 will be shorter to accommodate the tilt bar ears 62 of the carriers 35.

As seen in Fig. 4, the resilient sealing strip 78 is held by the flanges 79 in close association with the slat carrier for swinging movement therewith and the bowed web of the sealing strip presses into frictional sliding engagement with the opposed face of the jamb flange. As a result of the relatively broad, snug intersurface engagement of the sealing strips 78 and the jamb strip surfaces, and the sealing engagement of the strip flanges 79 with the carrier, wind or rain are effectively excluded and the passage of light is prevented at the ends of the louver slats when the louver is closed.

There is no leakage between the adjacent ends of the sealing strips 78 because of the overlap permitted in the closed condition of the louver

by notches 81 at their lower or outer ends corresponding to the overlap groove clearance notches of the slat carriers. Thus, the sealing strips form, in effect, a continuous seal between the slat carriers and the entire lengths of the jamb strips from below the top of the stop strip 21 to above the lower edge of the upper sealing strip 22 of the window frame. There can, of course, be no leakage between the jamb strips and the jambs because of the overlapping attachment of the strip flanges 29 and 48 to the jambs.

In order to permit equalization of pressure of the sealing strips 78 at the opposite ends of the respective louver slats 19, the slat carriers 35 and 47 are preferably mounted for a slight amount of play axially of the pivot rivets 34 and 53. The inherent springiness of the jamb strip material also assists in this as well as in the sealing cooperation therewith of the strips 78 because of the spacing of the flanges 32 and 51 from the jambs.

Installing of the louver 19 is a simple and expeditious operation which calls merely for securing the pre-assembled (at the factory) slat carrying unit 24 and 25 in place on the jambs 11 and 12, respectively, securing the operating unit 27 in place and connecting the operating arm 71 to the link 74. Then the slat-end carriers 35 and 47 are swung to a convenient angle, such, for example, as shown in Figs. 5 and 6, and the louver slats 19 are slid into place, and the locking tongues 48 and 58 are bent over into locking position and the installation is complete and ready for use.

It may be noted that the position of the locking tongues 48 and 58, respectively, while straight before bending into locking position, is such as to facilitate assembly of the louver slats by serving as guides for locating the slats preparatory to sliding them into the carriers. Thus, the locking tongues 48 have been formed at the upper sides of the carrier channels, so that the end edges of the slats may be brought to bear thereagainst because the carriers 35 are held substantially immobile by the operating unit 27. On the other hand, the locking tongues 58 on the opposite carriers 47 are located on the lower side of the channel since these carriers are, until the slat boards are assembled therewith, freely rotatable on their pivot axes, limited only by the frictional braking effect of the associated resilient sealing strips 78. Therefore, it may be necessary, during the installation process, to straighten out certain of the slat carriers 47 into alignment with the slats before the slats can be slid into place therein. The unbent locking tongues 58 provide convenient locating guides for this purpose.

Because of the freedom from direct fastening of the slat carriers 35 and 37 to the supported slat ends, the invention is very well suited for use with slats made from a transparent or translucent material such as glass or one of the plastic substances or even metal into which it would be impossible or impractical to drive nails, screws or other fastening means.

From the foregoing it will be apparent that our invention has resulted in substantial improvements in tropical louver construction, among which may be mentioned in summary: The pre-assembled unit construction of the slat-carrying hardware and the operating mechanism which reduces to three the hardware parts to be installed for a complete louver; the adaptability for assembling the louver slats after the hardware has been secured in place, whereby the slats may be accurately fitted as to any variable length

without any need for refitting or adjustment for the use of filler strips or blocks; the ease with which the louver slats may be replaced, if desired, merely by opening the locking tongues and sliding out any slats that need replacement; and the effective manner in which all joints between the louver and the window frame structure and between the slats themselves, as well as the adjacent structure, are sealed not only against the weather but also against the entrance or escape of light through the louver, which makes our louver particularly adaptable for use in barracks or other buildings of a military value or which might serve to guide an enemy if light were visible through the window opening at night.

While the invention is susceptible of various modifications and alternative constructions, we have shown in the drawings, and have herein described in detail, certain preferred embodiments, but it is to be understood that we do not thereby intend to limit the invention to the specific forms disclosed, but intend to cover all modifications and alternative constructions falling within the spirit and scope of the invention as expressed in the following claims.

We claim:

1. A tropical louver construction comprising a pair of vertically disposed jamb strips each associated with a window jamb, each of said jamb strips being of L-shaped cross section and possessing inherent springiness, corresponding sides of such strips being disposed in the same vertical plane and being attached to their associated window jambs, the other sides of said strips being substantially parallel with each other and spaced inwardly away from their associated window jambs, channel shaped slat carriers having their web portions pivotally mounted on and against said last-mentioned jamb strip sides, each of said slat carriers receiving an end of one of a plurality of louver slats, each of said slat carriers presenting to its associated jamb strip side a yielding convex surface afforded by a thin resilient channel, having a transversely curved web portion, which snugly receives such slat carrier and is interposed between the latter and the associated jamb strip side to provide light-tight joints between the end of the slats and said jamb strips when the slats are closed.

2. A tropical louver construction comprising a pair of vertically disposed jamb strips each associated with a window jamb, each of said jamb strips being of L-shaped cross section and possessing inherent springiness, corresponding sides of such strips being disposed in the same vertical plane and being attached to their associated window jambs, the other sides of said strips being substantially parallel with each other and spaced inwardly away from their associated window jambs, channel shaped slat carriers having their web portions pivotally mounted on and against said last-mentioned jamb strip sides, each of said slat carriers receiving an end of one of a plurality of louver slats, each of said slat carriers presenting to its associated jamb strip side a convex transversely curved surface against which such jamb strip side, being inherently springy and spaced from its associated window jamb, bears yieldingly and coextensively when the louver slats are in their closed positions to provide a substantially light-tight joint.

3. In a louver construction adapted to provide a light-tight closure for an air and light opening of an enclosure, a hardware unit, installable as such, comprising: a jamb strip which possesses

inherent springiness and includes a first flange adapted to be secured to one side of the air and light opening and a second flange integral with and extending from said first flange, said second flange being spaced inwardly away from its associated side of the opening, and a plurality of slat-carrying members elongated in the direction of the width of the slats to be received therein and intermediately pivoted to said second flange, said slat-carrying members presenting to said second flange surfaces which are transversely convexly curved and snugly coextensively engaged by said second flange in order to provide light-tight joints between said slat carrying members and said flange surfaces.

4. In a louver construction for black-out, the combination of a window frame with a pair of louver-supporting angles, each angle having a flange overlapping the exterior of the window frame and another flange at right angles for supporting the slat carriers, said window being formed at its upper frame member and its lower frame member with crack-closing members for overlapping the edges of the upper and lower louvers, a plurality of slat carriers pivotally mounted on each of said angles and regularly spaced from each other, the slat carriers on one angle member being in alignment with the slat carriers on the other angle member, each slat carrier being formed with a supporting body pivotally mounted on the angular member with a pair of transversely extending retaining flanges for engaging the front and back of a slat and retaining flanges for engaging the edges of the slat, 35 a plurality of nonmetallic slats mounted in said slat carriers and confined therein by the transversely extending flanges thereof, said slats and slat carriers being so arranged that the slats are overlapping when closed, a connecting bar pivoted to the edge of the slat carriers on one angle to move all the slat carriers and slats together, means for actuating said bar whereby the slats may be pivoted into open or closed position, and 40 resilient crack-closing members carried by the end of each slat assembly between the slat carrier and the angle member comprising a resilient sheet metal member which is bowed transversely to the thickness of the slat for engagement with the angle member along a line of contact and 45 having transversely extending embracing flanges which engage outside of the slat-supporting flanges on each carrier whereby the crack is closed between each slat carrier and the angle member to prevent discharge of any light when the louver 50 is closed.

5. In a tropical louver construction adapted to utilize louver slats and to provide a light-tight closure for an air and light opening in a wall, a hardware unit comprising a jamb strip adapted to be secured in light-tight relation along one side of the opening, and a plurality of slat carrying members rotatably secured to said jamb strip in spaced relation such that their ends overlap when said members extend along said strip, each 60 of said slat carrying members including a first channel adapted to fit snugly over the end of a louver slat and having end tabs holding the louver in place, and a second channel fitting snugly over the sides of the first channel and 65 having a convex resilient web adapted to engage said jamb strip to form a light-tight joint between the slat carrying members and the jamb strip along the width of the slat.

WILLIAM A. ANDRESEN.
LOUIS BOERO.
